UNITED STATES PATENT OFFICE.

WILLIAM A. PERRY, OF WORCESTER, MASSACHUSETTS, ASSIGNOR TO M. J. WHITTALL, OF WORCESTER, MASSACHUSETTS.

DESIGN FOR CARPET.

No. 37,676.

Specification for Design.

Patented Nov. 14, 1905.

Application filed September 29, 1905. Serial No. 280,719. Term of patent 3½ years.

To all whom it may concern:

Be it known that I, WILLIAM A. PERRY, a citizen of the United States, residing at Worcester, in the county of Worcester and State of Massachusetts, have invented a new, original, and ornamental Design for Carpets, of which the following is a specification.

The drawing shows a plan view of the carpet.

I claim—
The ornamental design for carpet as shown.

WILLIAM A. PERRY.
